9	9	9
10	X	X

INSTRUCTIONS TO BANK.—HOW TO ISSUE

1. Have Depositor write name and address on Signature Card.

2. Punch through all the sheets in the schedule at the bottom, the date of deposit according to the form on the Signature Card. (The schedules are so arranged that the same stroke of the punch will indicate on the Signature Card, Pink Sheet and Certificate the date of deposit, and on each Interest Check, its own proper date of maturity.)

3. Punch through all the sheets in the schedules at the left-hand end of the Signature Card, the amount deposited. (The schedules are so arranged that this same stroke of the punch will indicate on the face of the Signature Card, Pink sheet and Certificate, the amount deposited. It will also automatically calculate the interest, and show on the face of each Interest Check, its own value.)

4. Fill out and sign Certificate of Deposit (last sheet) in ink.

5. Detach and retain first two sheets (Signature Card and pink sheet) and deliver remainder to the depositor.

DUE DATE OF FIRST INTEREST CHECK IS PUNCHED HERE.

Jun	May	Apr	Mar	Feb	Jan	Dec	Nov	Oct	Sep	Aug	Jul	Jun

UNITED STATES PATENT OFFICE.

CHARLES HALL DAVIS, OF PETERSBURG, VIRGINIA.

INTEREST-BEARING INSTRUMENT OF OBLIGATION.

1,114,342.

Specification of Letters Patent.

Patented Oct. 20, 1914.

Application filed May 1, 1909. Serial No. 493,436.

To all whom it may concern:

Be it known that I, CHARLES HALL DAVIS, citizen of the United States, residing at Petersburg, in the county of Dinwiddie and State of Virginia, have invented certain new and useful Improvements in Interest-Bearing Instruments of Obligation, of which the following is a specification.

My invention relates to improvements in interest-bearing instruments of obligation, such as bonds, certificates of deposit, and the like, the type of instrument being allied to that forming the subject-matter of Letters-Patent of the United States granted to me November 13, 1906, No. 835,703.

Interest-bearing instruments, such as bonds, as heretofore provided for commercial use, have been generally in a form requiring issue as of a particular date and for a specific purpose, the body of the bond containing the verbiage of the obligation, while the interest-coupons have a predetermined date of maturity initially placed thereon, coupons being detached at the date of maturity; where the bond is actually issued at a date subsequent to the date of maturity of any of the coupons, said coupon is detached prior to the actual issue. Owing to these facts, the issuance of interest-bearing instruments requiring a simultaneous issuance of subsequently-maturing interest-coupons has been (with the exception of the structure forming the subject-matter of the Letters-Patent heretofore referred to) confined mainly to bonds or such other obligation in which the date of issue for a plurality of separate obligations is the same; and this limitation in issue has been still further restricted by reason of the requirement that the purpose of issue must be stated therein. This restriction has been removed by the instrument which forms the subject-matter of said Letters-Patent, which permits of the application of the general features of a bond, (a simultaneous issue of the obligation and coupons) to other forms of obligation such as certificates of deposit, and the like, where the date of issue of a number of obligations need not be confined to a single date, and in which each obligation is issued for a fixed period beginning with the actual date of issue.

While the instrument referred to permits a wide expansion in the use of interest-bearing instruments which include the in-

terest-coupons, said instrument requires the insertion of dates and other data separately in the body of the certificate and in each coupon, as well as requiring the separate completion of a plurality of interest-coupons; and while it is possible to indicate the amount of the obligation and the amount of the interest of a plurality of coupons by punching certain indicia thereon, such punching requires the punching of the amount and the interest indicia separately, thereby permitting liability of error in punching to be present, there being no absolute assurance that the punched interest-indicia is the true interest-amount based on the rate of interest and the face value of the obligation.

The instrument forming the subject-matter of my present invention, like that of said Letters-Patent, provides for the use of coupons each of which has a face value of one per centum of the obligation, the number of coupons provided for each interest year corresponding to the rate of interest; for instance, if the rate of interest is three per centum, three coupons, each having a value of one per centum of the face-value of the obligation, are provided for each interest year, the dates of maturity of successive coupons being in successive intervals of four months. The present instrument, however, differs from that referred to in several essential features, these features combinedly providing for safety and economy in issue, and insurance against tampering with any portions of the instrument which would monetarily affect the instrument or contract entered into between the issuer and the person to whom issue is made, these forming the principal objects of the present invention. Among these features are the following: Arranging the instrument of obligation and the successive interest coupons in superposed relation, and providing each with indicia adapted to be punched to represent an amount, each having the indicia arranged to permit simultaneous punching of the parts of the instrument to indicate the face value of the obligation and the amount of the face value of each interest coupon, thereby providing against liability of error in relative amounts of interest computation and amount of obligation, and also providing that each part of the instrument carries both amounts, one serving as a check.

against inaccuracy of the other. Arranging the superposed parts indicated with successively arranged month and year indicia, and also with date of the month indicia, said indicia being arranged on the several parts, to indicate the date of issue and of maturity of the several parts of the obligation, these dates being provided by simultaneous punching of the parts. Providing an interest-bearing instrument of obligation having attached interest coupons, with a detachable receipt acknowledging the issue of the instrument of obligation and bearing the signature of the recipient, said receipt carrying indicia indicating the face value of the instrument, the amount of each interest-coupon, the date of issue of the instrument, and the date of one interest-payment, said indicia being arranged to be punched simultaneously with similar indicia carried by parts of the instrument, thereby providing a record in the hands of the issuer by means of which the several parts issued to the recipient may be identified and checked against change or tampering. Providing an interest coupon with permanent indicia indicating the amount of principal and interest arranged to be simultaneously punched, and also indicia indicating the date of issue of the instrument and of maturity of the coupon also adapted to be punched simultaneously. Providing a plurality of superposed interest-coupons each having indicia for indicating any single date within a predetermined period of time, said indicia being arranged in such manner that simultaneous punching of the indicia of the superposed coupons will provide successive dates of maturity corresponding to the interest-period covered by the amount of interest indicated as the face-value of the coupon.

To these and other ends, the nature of which will be readily understood as the invention is hereinafter disclosed, said invention consists in the improved arrangement and combination of parts hereinafter fully described, illustrated in the accompanying drawing, and particularly pointed out in the appended claim.

50 In the drawings, in which similar reference characters indicate similar parts in each of the views, Figure 1 is a view of the face of the book. Fig. 2 is a view of the reverse side of the upper or "signature card" sheet of the book. Fig. 3 is a view of the face of one of the interest coupons. Fig. 4 is a view of the reverse side of the same. Fig. 5 is a view of a fragmentary portion of the obverse face of one of the interest coupons, the portion shown being the date indicia of the interest coupon for the interest period succeeding that shown in Fig. 3. Fig. 6, is a view similar to Fig. 5, showing the indicia for the succeeding interest coupon following that disclosed in Fig. 5.

Fig. 7 is a view of the face side of a certificate of deposit included in the instrument. Fig. 8 is a view of the reverse side of the same. Fig. 9 is a perspective view of the instrument complete prior to being issued.

The instrument of obligation forming the subject-matter of the present invention, in its unissued condition, consists of a "signature card" A; a plurality of interest coupons B, and a certificate of deposit C. It may also, if desired, include an agreement D between the issuer of the certificate and the person or company authorizing the use of the instrument. These cards, leaves or slips, are of substantially equal size and perforated adjacent the binding thereof, as at 10, to provide an extension which serves to receive the means for securing the cards or leaves together, this means being shown in the drawings as a pair of staples 11 of any preferred design. When secured together in this form, the entire instrument is in the form of a book having detachable leaves, the preferred arrangement of the leaves being the following in successive order from the face of the book: the signature card A, the agreement D, the interest-coupons B successively arranged according to their dates of maturity, and the certificate of deposit C.

As in the case of the patented instrument hereinbefore referred to, the successive interest periods are arranged in such manner that each interest coupon exactly covers the interest-amount on the principal on a basis of one (1%) per centum, this arrangement being provided by dividing the year into the proper number of successive interest periods to provide for such one per centum rate. By this arrangement the face value of any one interest-coupon will be exactly one one-hundredth of the principal. In the prior construction indicated the use of two sets of indicia on each coupon enabled a comparison of punched indicia to ascertain the correctness of the interest computation, but, by reason of the fact that the two sets of indicia require separate punching, the presence of a discrepancy between the punched indicia would not indicate whether an error was made at the time of issue or was produced by clever manipulation of punchings. Another possible source of error-making is produced by the requirement of punching a series of double indicia, the instrument referred to providing a series of coupons on one leaf sufficient in number to cover the period of a year. And in said prior instrument, the certificate of deposit did not bear punched indications of the amount, the latter being written on the face of the certificate. In the present arrangement of the instrument these difficulties are met by arranging the indicia of the several parts of the instrument in such

manner that a single punching of the signature card to indicate the amount deposited will provide a punched record in each of the parts to show the amount deposited and the face-value of each interest coupon, thereby insuring the correctness of every part of the instrument, requiring a checking of but one amount. This amount-indication is not only present in the interest-coupons, but also in the certificate of deposit. This result is obtained by the following arrangement of indicia: At a suitable point on each of the parts of the instrument, shown at the left in the drawings, a space is provided in which a plurality of vertical rows of integers in numerical order are arranged, the arrangement of integers being the same in each row or column with the exception of the lower integer, which, in the form shown in the drawings, has the integer "10" as the lower integer, the corresponding space in the remaining columns being indicated as "X." These rows form the indicia for indicating the amount. Where the indicia is intended to indicate the amount deposited, the several rows are successively headed "Thous," "Hunds," "Tens," "Dolls," the reading being from left to right where the deposit is indicated on the obverse face of the part, and in the reverse direction (from right to left) where the indicia is arranged on the reverse face. Where the amount punched is to indicate the face-value of one interest-coupon, the headings are successively indicated as "Tens," "Dolls," "Dimes," and "Cents," the reading of the headings being from right to left when the indicia is on the reverse face of a part, and from left to right when on the obverse face.

As the two indicia (the "Amount deposited" and the "Value of each interest check") are located on opposite faces of each of the parts and so located as to exactly register, and the reading of the headings of the two indicia is in exactly opposite directions, it will be seen that a punching of an integer of any row of the "Amount deposited" indicia will thereby produce a punched opening of the exact integer on the opposite side that will indicate one per centum of the integer representing the deposit. For instance, if the integers 1, 2, 3 and 4 of successive rows of the indicia shown in Fig. 1 be punched, to indicate the amount of one thousand, two hundred, three tens (thirty) and four (1,234) dollars, the indicia of the opposite side of the card shown in said figure (see Fig. 2) will show one ten, two dollars (twelve dollars), three dimes and four cents (\$12.34), an amount which is one per centum of the principal indicated by the punchings of the amount deposited. Where the amount deposited is \$10,000 (which is the maximum of the form

shown in the drawings), the lower integer of each column is punched, ("X" being used in this row to prevent confusion with the ciphers at the top of the columns forming the indicia) giving the value of the interest-coupon as "ten tens" or one hundred dollars. If the deposit is of an amount less than one thousand dollars, the column headed "Thous" has the "0" punched; and if the deposit should be of an amount such, for instance, as \$20, the integer "2" of the column headed "Tens" would be punched, the remaining columns having the "0" punched, one of the requirements of issue being that each column will have one integer punched, each part bearing the notice that it is "Good only when one space is punched in each column", thereby giving notice of the invalidating of the instrument if tampering is attempted.

The registering indicia described is provided on each of the parts of the instrument, the "Amount deposited" being placed on the obverse face of the "signature card" A, the agreement D, and the certificate of deposit C, and on the reverse face of each interest-coupon, the interest value being in each instance placed on the opposite side, appearing on the obverse face of only the interest-coupons B. As the parts are arranged in such manner that the indicia of all parts register with that of the upper part (the signature card A), it will be readily understood that a single punching will provide a permanent record on each sheet of the parts of the amount deposited and the value of the interest-coupons; it will also be seen that in each case the face value of the particular part having any monetary value (the interest-coupons and the certificate of deposit) is indicated on the obverse face of the part.

In the drawings, the indicia of the "Amount deposited" is designated 20 the indicia for the "Value of each interest check" being designated as 21.

The invention herein described not only provides for punched amount-indication for each part of the instrument, but, in addition, as heretofore stated, provides for an automatic indication of dates of deposit and maturity, by a single punching of the parts. This is provided by the following arrangement of indicia: On the obverse face of each of the parts of the instrument, are arranged a plurality of rows of date indicia, arranged in two divisions, viz.: a row or rows of successively arranged blocks or squares 25 divided to form a blank space and a space containing the name of a month and the year, and a row or rows of successively arranged integers from 1 to 31 to indicate the day of the month, the latter being indicated as 26. The first division has the month-names arranged in succession (shown 130

in horizontal rows in the drawings), the arrangement preferably being such as to provide for the inclusion of the twelve months of a year in a single row; in the drawings, 5 the successive arrangement covers a period of two years and eight months, each month having a blank space to permit of punching. The second division has the integers in numerical sequence, and for the purpose of 10 compactness the arrangement provides for one complete row and a part of another row. As in the case of the amount indicia, the reverse face of the instrument is provided with a similar arrangement of the date indicia, the reading being exactly reverse from 15 that of the obverse face, to provide for registration of punching spaces, the month-day integers being in exact registration. And while the arrangement of month-name and 20 year is in succession as on the front face, the month names and year differ on the opposite faces of the sheet.

As will be readily seen, the date indicia is so arranged as to permit of an indication 25 of a specific date between the extremes of the month dates shown in the squares 25, by the punching of the space alongside of the desired month and the punching of the proper month-day integer; for instance, in 30 Fig. 1 of the drawings, the punching is opposite the square for "March, 1909" and on the integer 5, this punching indicating that the date of deposit was March 5, 1909. Should the punch mark be placed on any 35 other square in addition to the two marks shown, it will be a clear indication of tampering and under the conditions of issue the instrument is rendered void. As will be readily understood any other date than that 40 indicated by the punched marks in Fig. 1 may be indicated, as long as the squares 25 contain the name of the month and the year in which the punching is to indicate the date.

45 As heretofore pointed out, the date indicia on the opposite face of either of the parts of the instrument is printed so that the indicia of both faces register, that on the reverse face reading from right to left 50 or in reversal to that of the obverse face. By commencing the successive month and year dates shown on the reverse face of the part with an earlier or a later month and year date from that beginning the series on the 55 obverse face, it will be obvious that a punching of a square on the obverse face to indicate one fact will provide a similar punching of a different month of the reverse face to indicate a different fact. This arrangement 60 permits of the obtaining of two distinct dates by a single punching the date indicia of the parts of the instrument; for instance, if the arrangement be such that the date indicia of the obverse face of the 65 interest coupons begins with the name of the

month which corresponds exactly with the beginning of an exact interest period with respect to the month name indication of the "date of deposit" date indicator, it will be readily understood that the punching of the date of issue will automatically give an indication of the date of payment or maturity of the interest coupon; or if the months and years of the opposite faces of the certificate of deposit be arranged to provide for the exact life of the certificate when issued, the single punching will indicate the date of issue and date of maturity of the certificate. This arrangement will be more fully understood by a reference to the drawings, in which it is assumed that the instrument was issued on March 5, 1909, and bears interest at the rate of three per centum per annum. As all of the date indicia of the several parts of the instrument are arranged to register, it will 85 be understood that the punching of this date as exposed on the signature card, provides a punching of dates throughout the instrument, and that where the indicia begins with the same month and year as that shown as beginning the date indicia of the obverse face of the signature card (the first month of the date indicia forming an index to the date indicia) such dates will be identical; this fact is made use of to indicate the 90 date of deposit on each leaf or part of the instrument, it being shown on the obverse face of the signature card, the agreement and the certificate of deposit, and on the reverse face of each of the interest coupons. 95 The first interest coupon has the indicia on its obverse face beginning with July, 1909, the fourth month after March, 1909, the interest periods being of a length of four months; therefore, when the date of issue 100 indicating the month of March, 1909, was punched, this punching simultaneously gave a punch indication of the month of July, 1909, which forms the date the interest represented by the coupon is due, in other 105 words, indicating the date of maturity of the coupon. The next interest coupon has its indicia beginning with the month of November, 1909, and the punching of the date of issue indicates that as the month containing 110 the date of maturity of that coupon. The succeeding interest coupon has its indicia beginning with the month of March, 1910, and each successive coupon is similarly arranged to provide for the several interest 115 periods, with the result that the obverse face of each interest coupon bears a punched indication of the date of maturity of the coupon, the punching being provided on the date of issue. 120

The indicia on the reverse face of the certificate of deposit shown in Fig. 8 begins with the month of March, 1911, that being the date of the last interest payment and of maturity of the certificate, the instrument being 125 130

issued to mature at the end of two years. As will be understood, therefore, those parts of the issued instrument which have a negotiable monetary value, viz., the certificate of deposit and the interest-coupons, each contain permanent indication (by punching) of the date of deposit, the amount of deposit, the face value of the part, and the date of maturity; in addition, the certificate of deposit bears an indication of the amount of each interest coupon. Owing to the fact that the date of maturity is not essential on the signature card and the agreement (these having no negotiable monetary value) a punched indication of such date is not given, the indicia providing for an indication of the date when the first interest coupon matures; this provides a check against the use of a stolen form from which the interest coupons have been detached, the position of the punch marks and the particular index month shown at the beginning of the indicia serving to guard against fraud in this connection, it being readily understood that calculations based on the showing of the signature card in possession of the bank in connection with the consecutive numbering of the interest coupons, permits of a ready comparison and checking.

As shown by the drawings, each of the several parts of the instrument contains printed matter specific to the part on which it is contained, each part, however, containing reference to the punched data. This specific matter will now be pointed out in detail.

The signature card A is a receipt, signed by the depositor for the coupon certificate of deposit, and contains, in common with the remaining parts of the instrument, the cautionary notice relative to the invalidity of the instrument by incomplete or excessive punching. The reverse face of this card (shown in Fig. 2) contains specific instructions relative to the completion of the instrument. This card remains with the issuer of the instrument.

The obverse face of each interest coupon B (see Fig. 3) contains the promise to pay the amount punched in the amount indicia on the date indicated in the date indicia, the coupon having a number showing its relation to the remaining interest coupons of the instrument, and also bearing the number of the instrument, the latter being the only portion of the check or coupon which is not provided with the instrument as printed, it being understood that the check will contain the signature of the person authorized to sign it either in written or printed form.

The indicia on the obverse face of the check or coupon is punched to indicate the face value of the check or coupon and its date of maturity. The reverse face of each interest check or coupon (see Fig. 4) contains information indicating the manner of its use,

and the caution relative to the perfect punching of the check, and indicia showing the amount and date of deposit.

The obverse face of the certificate of deposit C (shown in Fig. 7) is provided with suitable spaces to receive the written data of the deposit and as the facts contained therein must agree with the punchings of the indicia contained thereon a check against fraud and error is thereby provided; the obverse face also contains instructions as to when the certificate must be redeemed. The reverse face of the certificate (shown in Fig. 8) contains instructions as to the manner in which the certificate may be used together with a space for the signature of the depositor; the indicia contained on the reverse face indicates the face value of each interest check and the date of maturity of the last interest check, this also indicating the date of maturity of the instrument as further interest will not be paid on the certificate after that date. The agreement D contains the same indicia as is contained on the signature card in addition to the agreement between the issuer of the certificate and the provider of the complete blank.

The advantages of the form of instrument herein described are generally set forth above. In addition, however, it is to be noted that the fact that date of issue is placed simultaneously on all of the parts of the instrument in a manner which will prevent fraud, enables the use of a printed form bearing detachable interest-coupons, simultaneously completed with the punching of the certificate of indebtedness. Another advantage lies in the fact that a single punching indicates the amount or face value of both principal and individual interest indebtedness together with the dates of interest payments and maturity of the obligation. In addition, the use of a signature card provides a permanent record in the hands of the party issuing the instrument by means of which he is able to absolutely check the remaining portions of the instrument which passes out of his hands at the time of issuance, and as said card contains the signature of the depositor, it provides a protection to the issuer against claim of fraud in case the signature on the card A and certificate C are not in strict accord; if not in such accord, the signature card will provide record evidence on which to base a refusal to meet the obligation when presented at maturity.

Having thus described my invention, what I claim as new is:

An instrument of obligation comprising a plurality of superposed leaves, said leaves consisting, respectively, of a signature certificate, an agreement certificate, a deposit certificate, and a plurality of interest coupons, said signature, agreement and deposit

certificates having their upper faces provided with deposit indicia at one end and deposit date indicia extending longitudinally thereof, the reverse faces of said certificates having interest indicia of like numerals of different denominations to that of said deposit indicia of the front faces and in register with same, said reverse faces of said certificates also having instrument life date indicia extending longitudinally thereof and in registry with said fixed date indicia of the upper faces, said interest coupons each having its upper face provided with interest indicia at one end and date indicia extending longitudinally thereof to designate the date of maturity of each coupon, the reverse face of each of said coupons having deposit

indicia at one end thereof of like numerals of different denominations to that of said interest indicia, and in registry with same, 20 said reverse faces of said coupons also having deposit date indicia in registry with the interest date indicia of said upper faces, said deposit and interest indicia being acted upon simultaneously by a single operation, 21 said date indicia also being acted upon simultaneously by a single operation.

In testimony whereof I affix my signature in presence of two witnesses.

CHARLES HALL DAVIS.
